UNITED STATES PATENT OFFICE.

WILLIAM A. CARSON, OF DENVER, COLORADO, ASSIGNOR, BY MESNE ASSIGNMENTS, TO KITCHEN SERVICE COMPANY, OF CHICAGO, ILLINOIS, A CORPORATION OF ARIZONA.

DISH-WASHING MACHINE.

1,180,471.

Specification of Letters Patent. Patented Apr. 25, 1916.

Application filed October 21, 1915. Serial No. 57,122.

To all whom it may concern:

Be it known that I, WILLIAM A. CARSON, a citizen of the United States, residing at Denver, in the county of Denver and State 5 of Colorado, have invented certain new and useful Improvements in Dish-Washing Machines, of which the following is a specification.

This invention relates to a machine for 10 washing dishes, and other similar articles used in the preparation and serving of food, and to a novel construction and arrangement of its component parts.

In carrying into effect the present invention, I employ a trough-like chamber for the 15 cleansing fluid, and a shaft within the chamber, having a series of splashers arranged to carry the fluid into forcible contact with the dishes and other articles which are supported within an open receptacle immediately adjacent the splashers.

Among the objects of my invention I have sought to provide a machine which is simple 20 and inexpensive, and effective for washing dishes as well as other articles, such as glassware and cutlery; a machine which will operate with equal effectiveness, regardless 25 of the direction in which the splashers may be rotated; and a form and construction of splashers which will insure the greatest efficiency in the washing operation. These and other objects of my invention will more fully hereinafter appear from the specification 30 and claims, and from the drawings in 35 which:—

Figure 1 is a vertical section through a washing machine embodying the principles of my invention; Fig. 2 is a horizontal section through the machine, taken on line 2—2 40 of Fig. 1; the basket being removed in this view; Fig. 3 is a transverse section through the machine, taken on line 3—3 of Fig. 1; and Fig. 4 is a detail, in perspective, showing one of the splashers which are mounted 45 upon the shaft.

A representative embodiment of my invention is shown in the drawings in which is exhibited a housing 5, the bottom portion 6 of which is shaped to provide in effect a trough for the cleansing fluid. The housing 50 may be supported on legs 7, as shown. The upper portion 8 of the housing is shaped to provide a chamber for the reception of an open basket 9, arranged to seat upon brackets or braces 10. This basket I prefer to

equip with a series of racks 11 against which dishes may be stacked, these racks being conveniently formed of wire or other similar material bent in zig-zag form and arranged in parallel courses. A smaller basket 12 is 60 also shown, within which articles of cutlery may be placed for the washing operation. The housing is rendered water tight by the use of a cover 13, which may be secured in place by any appropriate means.

Extending from one end of the housing to the other is a shaft 14, preferably square in cross section. The ends of this shaft are suitably journaled within bearings 15, one end 16 of the shaft extending through the 70 housing to the exterior thereof. Upon this end of the shaft a sprocket wheel 17 is mounted. A sprocket chain 18 passes over the wheel 17, and over another wheel 19 of relatively greater diameter, which is rotatably mounted upon the exterior of the 75 housing. A handle 20 is secured to the sprocket wheel 19 for the purpose of rotating the same, in consequence of which the shaft 14 may be revolved at high speed. A series of splashers 21 are mounted upon the shaft 14, being arranged progressively 90° apart. As best shown in Fig. 4, these splashers consist of two complementary sections, 80 each conveniently formed from a single 85 piece of material by the use of a die. Each of these sections moreover is constructed to provide a relatively hollow portion 22, side walls 23, and an inclined end wall 24. The end of each section which is secured to the 90 shaft 14 is also shaped to squarely embrace the shaft, a portion 25 thereof being extended a slight distance to overlie the shaft. When two such sections are laid back to back 95 on opposite sides of the shaft, they may be conveniently secured in place by fastening means, such as rivets 26, all as clearly illustrated in the several figures of the drawings. An inlet 27 is shown for admitting liquid to the housing where plumbing connections are 100 established, and a drain 28 for discharging the liquid therefrom. Such connections are especially desirable where the machine is used considerably, and where it is required that frequent changes of water be made in 105 the housing. The manner in which these splashers are arranged upon the shaft is of special importance. As appears in the drawings, the splashers are arranged progressively 90° apart, two splashers separated 110

by a considerable distance being alined on the same side of the shaft where eight splashers are employed, as shown. It is manifest as soon as two splasher are 5 revolved out of the body of the cleansing fluid that the adjacent splasher situated 90° therebehind, will be the next to leave the body of the fluid, and so on. In this manner the liquid is agitated progressively in different sections, corresponding to the planes 10 in which the several splasher are located. This action of the splasher in a high speed machine is more effective than any other, since otherwise each splasher would be required to work in a void within the liquid 15 body created by the movement of the preceding splasher. Under the arrangement which I have adopted, such an inefficient principle of operation is overcome, each 20 splasher performing its work at points where the water is at the moment relatively undisturbed.

In throwing the water forcibly into contact with the dishes to be cleansed, the form 25 of splasher, best shown in Fig. 4, is particularly effective. This is due to the fact that the side walls 23 retain within the hollow portion of each splasher a considerable quantity of water, which by centrifugal action 30 is discharged over the inclined end 24 of the splasher. The action of these splasher is comparable to that of a bucket to the extent that a certain quantity of water is 35 lifted out of the body of liquid which fills the bottom of the housing, but is dissimilar in that the inclined end wall 24 is shaped to facilitate the discharge of practically all the water from the splasher shortly after it has been revolved clear of the body of the liquid. 40 The open receptacle for the dishes which is situated immediately adjacent to the splasher enables the water so discharged from the splasher to come into forcible contact with the dishes, and thereby exert a cleansing action thereupon. The particular direction 45 from which the water is thrown depends largely upon the direction in which the splasher are rotated. In the construction which I have shown, the splasher is formed 50 of two complementary parts, neither of which interferes with the action of the other, yet either of which may operate independ-

ently of the other when the shaft 14 is rotated in the proper direction. It may frequently be desired that the splasher be 55 revolved first in the one direction and then in the other, for the purpose of directing the action of the water upon the dishes from opposite sides of the housing, and such a reversible action may be effectively accomplished with the present construction of splasher.

I claim:

1. A dish washing machine including, in combination, a liquid retaining receptacle, 65 a rotatable shaft, and a plurality of splasher mounted radially upon the shaft and arranged to be revolved through the body of the liquid, said splasher being provided each with a hollow portion, the bottom of 70 which is in radial relation to the shaft, each of the splasher having an end wall inclined with respect to its bottom over which liquid may be discharged by centrifugal action when the splasher is rotated in the 75 proper direction, substantially as described.

2. A dish washing machine including, in combination, a liquid retaining receptacle, a rotatable shaft, and a plurality of splasher carried by the shaft arranged to be revolved through the body of the liquid, said splasher comprising each two (2) complementary sections secured back to back with a portion of each embracing the shaft, and each said splasher section being provided 85 with a hollow portion and an inclined end wall over which liquid may be discharged by centrifugal action when the splasher is rotated in the proper direction, substantially as described. 90

3. In a machine of the class described, the combination with a shaft of a splasher consisting of two (2) complementary sections, each formed with side walls and inclined end walls, the end wall of each section adjacent the shaft being extended to overlie and embrace the shaft, and means for securing each section to the other, said means serving also to lock the splasher upon the shaft, substantially as described. 95
